UNITED STATES PATENT OFFICE.

WILLIAM J. McSWEENEY, OF CHICAGO, ILLINOIS.

DESIGN FOR A COIN.

Application filed February 25, 1924. Serial No. 8,732. Term of patent 3½ years.

To all whom it may concern:

Be it known that I, WILLIAM J. McSWEENEY, a citizen of the United States, residing in Chicago, county of Cook and State of Illinois, have invented a new, original, and ornamental Design for Coin, of which the following is a specification, reference being had to the accompanying drawing, forming part thereof, in which—

Fig. 1 is a plan view of one side of the coin, and Fig. 2 a plan view of the opposite side of said coin; Fig. 3 is an edge view. These figures illustrate my new design.

I claim:

The ornamental design for a coin, as shown.

WILLIAM J. McSWEENEY.
